UNITED STATES PATENT OFFICE.

JOHN ALLENSON, OF ST. PAUL, MINNESOTA, ASSIGNOR TO ST. PAUL FOUNDRY COMPANY, OF ST. PAUL, MINNESOTA, A CORPORATION.

HYDRAULIC JAIL-DOOR-LOCKING MECHANISM.

Application filed June 12, 1919. Serial No. 303,756.

To all whom it may concern:

Be it known that I, JOHN ALLENSON, a citizen of the United States, residing at St. Paul, in the county of Ramsey and State of Minnesota, have invented a new and useful Improvement in Hydraulic Jail-Door-Locking Mechanism, of which the following is a specification.

This invention pertains to jail door locking and unlocking mechanism, which is operated by hydraulic means in a simple, positive and effective manner and particularly where it is desired to operate a series of jail door locks simultaneously, to either unlock or dead-lock the locking mechanism of each of the cells or to position the locking mechanism of the cells so that the same can be operated by individual keys to unlock any of the cells individually.

It is undesirable to have any complicated mechanism for locking or unlocking jail doors, especially mechanism which may easily get out of order and which requires considerable attention. This invention overcomes these difficulties in an extremely simple and effective manner, by a combination of elements which securely lock each and every cell and by a hydraulic means which operates the locking mechanism of each cell into either a dead-lock position or other positions that may be desired.

The hydraulic operating mechanism is extremely simple, being controlled by a master valve, and operates means which is connected with a series of cell locking means so that when the hydraulic means is operated, the cell locking mechanism is also operated, but the hydraulic mechanism is not for the purpose of opening by actually engaging and pulling the cell doors. Thus, the hydraulic operating means is independent of the actual opening of the cell doors and is operated in a peculiar manner, which is very effective in operating the mechanism connected to the same.

The door locking and unlocking mechanism for a series of doors can be operated by hand, particularly where the gang controlling mechanism is used in connection with a series or tier of straight cells, that is, cells that are not arranged in a circle or curve, and which do not require the power for operating the same that is necessary in cells arranged in a curve. This is clearly evident

from the fact that the operating bar or gang control is practically straight when the cells are arranged in a straight line.

An important feature of this invention is a simple means for illustrating to the jailer the position of the gang operating bar and lock controlling mechanism, so that in operating the same, the jailer can see, at a glance, just what position the gang-bar is in and thus know, from the relative position of the gang control, the position of the individual door locks and locking bars.

The features and peculiar arrangement of parts will be clearly defined and set forth in the specification and claims.

In the drawing forming part of the specification:

Figure 1 is a diagrammatic plan view of a circular prison, illustrating the position of the cells in the same.

Figure 2 is a diagrammatic cross sectional elevation of a portion of the prison construction.

Figure 3 is a front elevation of a portion of the cells, having a portion broken away to disclose the operating parts in the mechanism compartments.

Figure 4 is a front elevation of a portion of a cell and the locking mechanism in open position.

Figure 5 is a detail of a portion of the locking mechanism partly illustrated in cross section.

Figure 6 is a perspective view of one of the cell door locking bars.

Figure 7 is a vertical sectional view of a portion of the cell on the line 7-7 of Figure 3.

Figure 8 is a vertical section on the line 8-8 of Figure 3, a portion of a division wall being broken away.

Figure 9 is a sectional plan view on the line 9-9 of Figure 3.

Figure 10 is a plan view of the master valve.

Figure 11 is a sectional side elevation of the master valve on the line 11-11 of Figure 10.

Figure 12 is a diagrammatic plan view, illustrating the position of the master valve and the hydraulic cylinders, as they would be located in the circular prison of the construction illustrated in Figure 1.

Figure 13 is a front elevation of a por-

tion of a series of cells, illustrating the locking mechanism in open position and the gang controlling means operable by hand.

Figure 14 is an end view of the hand operated means, illustrated in Figure 13, which also illustrates a device to indicate the position of the locking mechanisms.

The drawing illustrates a circular prison A, having a series of cells B positioned 10 circularly so as to make up the cell construction. The doors C of the cells B are positioned on the inner portion of the cells and are in full view of the jailer or guard at all times when he is in the conning or 15 operating tower D. This construction of jail is desirable, as it permits each cell to have an outside window to admit light and air and gives a large corridor E about the conning tower D on the first floor. The 20 other floors of the jail are provided with circular balconies F in front of the cells to allow the prisoners from the cells to go in and out and leaving the center portion of the jail entirely open from the first floor 25 up, so that a skylight can be provided on the roof, thereby making a very light, airy and pleasant jail. This construction of jail is now in use and has been found to be most desirable.

30 The doors C of the cells B have rigidly attached thereto latch lugs 2, 3 and 4, which pass through suitable openings in the door jamb 5, and are adapted to be engaged by a single locking bar 6, which engages in 35 suitable notches in the lugs and which is slidably held to the inside of the door jamb 5 by the bolts 7, in the ordinary manner. The locking bar 6 engages in the notches of the lugs 2, 3 and 4 to hold the door C 40 locked when in closed position and it is desired to have the cell B locked.

Each cell B is provided with a key lock G for the door C, which engages the latch lug 3 when the door C is in closed position 45 and locks the latch lug 3 therein in addition to its being locked by the locking bar 6. Each of the door locks G contain the mechanism of the individual door lock 8 and the individual dead-lock 9, and which is of 50 ordinary construction so that when the cell locking bars are released from dead-locking position, any of the doors C can be opened by operating the locking mechanism in the locks G with the key which is provided for 55 the same.

The drawings illustrate the cell doors C, and the stationary front portions of the cells H made up of steel sash, having glass inserted and held therein to provide closed 60 fronts for the cells. Above the glass cell fronts a mechanism box or passageway J is formed, in which a gang-bar 10 is positioned. In the circular prison A, the gang-bar 10 is preferably practically semi-circular in shape and extends longitudinally

through the mechanism passageway J, it being obvious, however, that where the prison construction is such that the cells are positioned in line with each other and not on a curve, that the gang operating 70 such as 10, would be of a straight construction and would perform the same functions as will be described of the bar 10 in this construction.

The gang-bar 10 has cam members 11 75 rigidly secured thereto by the rivets 12, one cam member 11 being provided for each locking bar 6 and positioned at a point on the gang-bar 10 so as to operate the locking bar 6 when the gang-bar 10 is moved or reciprocated back and forth in the mechanism chamber J. The gang-bar 10 is held longitudinally, freely movable in the guide brackets 13, which are provided with horizontally extending rollers 14 that engage 80 the upper and lower surface of the cam member 11 and vertically extending rollers 15, which engage the sides or front and back of the cam member 11, while the guide brackets 13 are rigidly secured to the rear 85 wall of the mechanism chamber by the rivets 16. In this manner the gang-bar 10 is held freely movable longitudinally in the mechanism chamber J in either direction.

The locking bar 6 is pivotally connected 90 on its upper end to a yoke 17 by means of the connecting rod 18, and the yoke 17 is held freely slideable up and down under the strap 19, which is rigidly secured to the inner surface of the door jamb on one end 100 and to the division wall 300, which extends through the mechanism chamber on its upper end. The strap 19 is formed with a slot 20, through which the gang-bar 10 and cam member 11 freely pass, and the upper and lower surfaces of the cam member 11 105 engage the centrally positioned, horizontally extending rollers 21, which are freely held by the pin 22 in the yoke 17. Rollers or wheels 23 are positioned on either side of the rollers 21, and are of a larger diameter 110 than the rollers 21 so as to engage the strap 19, and the division wall 300 between which the yoke 17 is slidably held to hold the same freely movable up and down and to reduce 115 friction. The cam member 11 holds the yoke in position between the strap 19 and the division wall 300 and the rollers 21 and 23 allow the cam member 11 to be freely moved in either direction through the yoke 17.

The cam member 11 is formed with a depending cam portion 24, which engages the lower set of rollers 21 and 23 in the yoke 17, to hold the locking bar 6 in a downward, dead-locking position and holding the yoke 17 immovable up and down as the upper set of rollers therein engage against the surface 25 of the cam member which extends parallel to the upper surface 26 of the gang-bar, and the distance between the 120 125 130

said surface 25 and the depending portion 24, which has a surface that is parallel to the lower edge 27 of the gang-bar 10, is practically equal to the distance between 5 the upper and lower rollers 21 in the yoke 17. The cam member 11 is formed with a lower surface or edge 28, which extends parallel to the lower edge 27 of the gang-bar up to the inclined surface, which leads to 10 the depending surface 24. This edge 28 forms a space in conjunction with the edge 25 on the cam member 11 at the point 29, where the yoke 17 is held freely, to be moved upwardly by operating the key lock G, thus 15 giving a key releasing point at the point 29 on the cam 11, where the door C can be unlocked by operating the lock G in a manner as described and illustrated in my Patent Number 1,043,748. The position of 20 the yoke 17 on the cam member at the point 29 would be as illustrated in Figure 5, and this point would be the key opened position of the yoke 17 on the cam 11.

The doors C of ~~each~~ cell are hung at their 25 upper end on the rollers 30, in the ordinary, well-known manner, which rollers are adapted to travel ~~on~~ on the track 31 in the mechanism chamber J, allowing the doors C to be opened freely when they are un- 30 locked.

The shaft 32, which carries the roller 30, of each of the doors nearest the door jamb 5, has a ratchet bar 33 pivotally secured thereto on one end, which lies on the bottom of the mechanism chamber J and is engaged by a ratchet pawl 34, which is pivotally secured at 35 in the mechanism chamber J. The pawl 34 is provided with a laterally extending lug 36, which extends 40 in the path of the lug 37 formed on the back and projecting from the yoke 17, so that when the yoke 17 is elevated or raised by the cam member 11, the ratchet pawl 34 is disengaged from the teeth of the ratchet bar 33, leaving the same free to move in a direction to open the door C. This ratchet mechanism is for the purpose of preventing the door C from being opened after it has 45 been partially closed, when the locking bar 50 is in its downward position and the upper roller 21 of the yoke 17 is riding on the edge 25 of the cam member 11, as is illustrated in Figure 5. Thus, the ratchet mechanism 55 prevents any possibility of the door C being only partially closed, that is, closed all but a small crack, which would hardly be noticed by the jailer, the prisoner having the intent of preventing the lugs 2, 3 and 4 from being engaged by the locking bar and 60 afterward opening said cell. Thus making the locking mechanism positive in operation and preventing any danger of the door being held open slightly, so as to be opened afterward when the locking mechanism is 65 set in dead-locking position.

The ratchet bar 33 can be engaged by the pawl 34 on its free end when the door C is in wide open position, to hold the same against being closed if the gang-bar 10 is operated so as to release the pawl permitting it to drop into engagement with the bar while the door is opened. In this manner, any or all of the doors C can be locked open, if it is desired.

The cam member 11 is provided with an 75 upwardly projecting surface or edge 38, which extends parallel to the upper edge 26 of the gang-bar 10, and is for the purpose of engaging the yoke 17 to raise the same and cause the lug 37 to engage the lug 36 of the pawl 34, to release the pawl from the ratchet bar 33. This surface 38 is adapted to raise the locking mechanism into ratchet releasing position, as illustrated in Figure 3 of the drawings, but does not, however, 80 raise the unlocking bar 6 entirely out of engagement with the notches in the lugs 2, 3 and 4.

While the drawings illustrate the cam member 11 so constructed as to work in 90 conjunction with the yoke 17 to release the ratchet mechanism of each of the doors when the yoke is engaged by the edge 38 of the same, it is evident that the lug 37 on the yoke can be so positioned that the 95 yoke will only partially release the pawl 34 of the ratchet mechanism when the yoke 17 is engaged by the surface 38. If the construction of the yoke is such that the ratchet mechanism is only partially released 100 when engaging on the edge 38 and the locking bar 6 is only partially released, this position is desirable for relieving the wear on the lugs 2, 3 and 4 and the lug engaging slots formed in the locking bar 6, as 105 it will be evident that if the ratchet mechanism and the locking bars 6 are partially released, it is not necessary for the lugs 2, 3 and 4 to raise the locking bar so far to admit the lugs to lock the door C, and 110 thus the friction is reduced in closing the door of the cell and wear on the connecting parts is also materially reduced. In some instances, it is desirable to have the ratchet mechanism only partially released by the 115 yoke 17 when the same is engaging the surface 38. This is optional, however, with the jail engineers, as they sometimes prefer to have the ratchet mechanism entirely released at one position of the operating bar. 120

The cam member 11 is also provided with an upwardly projecting portion or edge 39, which is higher than the edge 38 and extends parallel to the upper edge 26 of the gang-bar 10. This edge engages the yoke 17 to raise it into uppermost or releasing position, as is illustrated in Figure 4, releasing the locking bar 6 from the lugs 2, 3 and 4 and the locking mechanism G, leaving the doors C of the series of cells 130

whose locking mechanism is operated by the gang-bar 10, to be opened simultaneously by operating the gang-bar 10 into the position illustrated in Figure 4. The gang-bar 10 operates the cam members 11 into four distinct positions, namely, dead-locking position when the yoke engages the surfaces 24 and 25, key opening position when the yoke engages at the point 29 and 10 is in the same position as it would be when in dead-locking position, hanging with its weight on the upper roller 21 in the yoke, engaging against the surface 25, but with the lower roller 21 free to move upwardly 15 to the point of engagement of the surface or edge 28, the third position being, the ratchet releasing point on the cam 11 when the yoke 17 is partly elevated by engaging the surface 38 thereon, and the fourth position being, the locked open point of the cam, in which position the locking mechanism is held open against being closed, except by the operation of the gang-bar 10.

A pointer 40 is rigidly secured to the gang-bar 10 so that a portion of the same is clearly visible through a glass 41, to indicate the different positions of the gang-bar 10 and the relative position of the locking and unlocking means. Said first above-named position is indicated by the letters D. L. at 42, the next by K. O. at 43, the third by R. R. at 44 and the fourth by L. O. at 45, all of which are clearly visible with the pointed end of the pointer 40 through the glass 41, as is illustrated in Figure 3 of the drawings. In this manner, the jailer can readily see the position in which the locking mechanism is at any time.

The gang-bar 10 is operated by fluid cylinders 46, having a piston 47 of ordinary construction, which operates or reciprocates the piston rod 48 and the free end of the piston rod 48 is freely slideable in the bearing 49. The cylinder 46, together with the bearing 49, are secured together and attached in a suitable manner to the upper portion of the mechanism chamber J, being so positioned as to be best connected to operate the bar 10. The piston rod 48 is connected with the bar 10 by means of the connecting arm 50, which is rigidly secured on one end to the piston rod 48, and the free end of which freely engages in the brackets 51, which is rigidly secured to the gang-bar 10 in a suitable manner, so that when the piston 47 is reciprocated in the cylinder 46, the arm 50 will operate the gang-bar 10 in a similar direction as the travel of the piston 47 in the cylinders 46.

The cylinders 46 are positioned in any suitable place in the mechanism chamber J to operate the gang-bar 10 most effectively, and for convenience Figure 12 of the draw-

ing illustrates, diagrammatically, the position of the cylinders in relation to the semi-circular operating gang-bar 10. This same figure also illustrates a master valve 52, positioned in the conning tower D, so that the jailer in the tower can operate the valve 52 to cause the cylinders 46 to operate the bar 10 in the desired direction. The cylinders 46 as shown in Fig. 3 are connected in series by the pipes 53 and 54, which lead from the master valve 52 to either side of the piston 47, and the pipes 53 and 54 connect with the passageways 55 and 56, respectively, which are formed on the cylinder and extend longitudinally of the same, the passageway 55 connecting with the piston chamber 57 at 58 on one side of the piston 47 and the passageway 56 connecting the piston chamber 57 at the other side of the piston 47 at the point 59 so that when fluid pressure is directed by the master valve into the pipe 53, the pistons 47 of the cylinders 46 will be operated in a direction to move the gang-bar 10 into unlocking position and in the direction illustrated by the arrow 60 in Figure 3, while when the fluid pressure is directed from the master valve into the pipe 54, the cylinders 46 will cause the gang-bar to be moved in the direction of the arrow 61, illustrated in Figure 3. Thus the pipe 53 will direct pressure to the cylinders 46 to unlock the mechanism of the cells simultaneously, or to move the gang-bar 10 into the position indicated by the pointer 40, and the pipe 54 from the master valve will cause the cylinders 46 to move in a locking position to dead-lock, if desired, all of the cells, simultaneously, whose mechanism is connected with the bar 10. It is obvious that the locking bar 10 could be a complete circle to operate all of the cells on one floor of the circular prison A, if it is desired, and if such were the case, the operating mechanism would accomplish the functions described in an equally efficient manner, but the drawing, for convenience, merely illustrates half of the cells on each floor, connected together by the gang-bar 10.

The master valve 52 is operated by the handle 62 to move the slide valve 63 in a direction to cause the fluid pressure in the pressure chamber 64 of the same to be directed into the passageways 65 or 66, which connect with the pipes 53 and 54, respectively. Fluid pressure is admitted into the pressure chamber 64 of the valve 52 by the inlet pipe 67, which is connected with any suitable source of fluid pressure to direct and maintain the desired amount of fluid pressure in the chamber 64 of the master valve at all times. The slide valve 63 is operated by the pinion 68, which engages with the rack 69 on the valve, the pinion 68 and the handle 62 being rigidly secured in a suitable manner to the shaft 70. In this man-

ner, the valve 63 is operated freely in the desired direction even when considerable pressure is exerted against the same by the fluid in the chamber 64.

- 5 It is desirable to use water or oil for fluid pressure in the operation of the locking mechanism in this device, but it is obvious that any other suitable fluid may be employed if it is desired, and also that air 10 pressure can be used, if it is so desired. The passageways connecting the master valve with the cylinders 46 are filled with the fluid which operates the pistons in the cylinders, and when the valve 63 is moved 15 into the position illustrated in dotted lines in Figure 11, fluid pressure will be directed to the pipe 54 through the passageways 66 to operate the piston 47 in the direction of the arrow 61 and operate the gang-bar 10 in a similar direction to locking position, the piston 47 forcing the fluid pressure on the other side of the same out of the piston chamber at 58 into the pipe 53, which becomes and performs the functions of an 20 exhaust pipe and causes the fluid therein to be directed back to the master valve and through the passageway 71 of the valve 63 and out of the master valve, through the exhaust port 72 into the exhaust pipe 73. If 25 the valve 63 of the master valve 52 is moved in the opposite direction to that illustrated in dotted outline in Figure 11, so that the pressure from the chamber 64 will be directed into the pipe 53 from the passageway 65, 30 then the pistons 47 of the cylinders 46 will move in an opposite direction and the pipe 54 becomes an exhaust pipe to exhaust the fluid from the cylinders 46 back to the master valve and into the exhaust pipe 73. 35 Thus the master valve will direct fluid pressure to either side of the pistons 47 of the cylinders 46 to operate the gang-bar 10 and to simultaneously operate all of the locking mechanism of each of the cells B, which are 40 connected to the same. It is essential, however, in the use of fluid pressure, that the connecting pipes and passageways, together with the cylinders 46, be filled with a fluid at all times, thus avoiding any jarring or sudden 45 jerking of the pistons and gang-bar 10 when the master valve is operated. The passageways leading from the passageways 55 and 56 at the points 58 and 59 are only large enough to admit the fluid pressure to 50 the cylinders 46 slowly, so that no sudden jar will be transmitted to the same and cause in uneven operation of the locking mechanism. 55 It is obvious that any suitable fluid pressure 60 can be connected to the intake pipe 67 of the master valve and that the exhaust pipe 73 of the same can be connected with an overflow or reservoir tank so that the fluid used in operating the cylinders can be used over and over again, and suitable 65 pumping mechanism, together with pressure regulating means, all of ordinary construction, connected with the same, it being essential, however, that the passageways be filled with fluid at all times so as to prevent air 70 from mixing with the fluid in the pipes and passageways and causing a chattering or uneven operation of the pistons 47 in the cylinders 46.
- It is obvious that one or more cylinders 75 can be used to operate the gang-bar 10, as occasion requires, this, of course, depending on the number of door mechanisms connected to the operating bar, Figure 1, illustrating, diagrammatically, the position of the 80 cylinders 46 in relation to the bar 10 when three cylinders are used for a semi-circular operating bar. This diagrammatic figure also illustrates the position of the master valve 52 in the jailer's conning tower D. The simple connecting of the cylinders 46 in series with the pipes 53 and 54 and to the master valve 52, reduces the piping to the cylinders to a minimum, and thus the pipes 52 and 54 perform the functions of inlet and 85 exhaust pipes at different stages in the operation of the pistons 47 in the cylinders. The fluid pressure inlet pipe 67 can be connected to the city water supply where sufficient pressure is maintained in the same to operate 90 the cylinders 46, thus eliminating the necessity of any pumping mechanism, there only being a small amount of fluid wasted when the cylinders are operated, as it is evident that the only fluid which will be exhausted 95 into the exhaust pipe 73 is that which is in the cylinders 46 and which is forced out of the same when the pistons 47 are moved in either direction.
- In connecting the cylinders 46 in series 100 by the pipes 53 and 54, with the master valve, and the particular construction of locking and unlocking mechanism, illustrated, a very simple, effective and practical jail locking and operating mechanism is provided, which is not apt to get out of order 110 or require considerable attention, this being a very important feature in a practical jail lock operating mechanism.
- In Figures 13 and 14 the gang-bar 10 is 115 moved back and forth by a hand operating mechanism K, which is positioned in a suitable enclosing box L at one end of the series of cells. In this construction, the gang-bar 10 has a threaded end 80 secured to the 120 same in any suitable manner, which is engaged by the sprocket wheel 81. The sprocket wheel 81 is held between thrust bearings 82 of any suitable construction by means of the bracket 83 and is operated by the sprocket chain 84, which passes over the sprocket wheel 85. The sprocket wheel 85 is adapted to be operated by a hand crank 86, in an ordinary manner, so as to rotate the sprocket 85 and drive the chain 84 to operate the 125 130

sprocket 81 in either direction. When the handle 86 is turned and the sprocket 81 is rotated, the threads formed on the inside of the same will engage the threaded end 80 to move the bar 10 back and forth, the bar 10 being held in suitable slots so as to prevent rotation of the same. By the hand operated mechanism K, the cams 11 connected to the bar 10 will be moved back and forth to operate the key lugs B and the locking bar 6 in similar positions and directions as operated by the hydraulic mechanism. This construction is particularly adapted to cell doors which extend in a straight line or plane with each other and in a prison construction where the cells are all positioned straight with each other and not on a curve. A suitable gauge 87, in the form of a weight or other suitable means, is hung by the cable 88 from the boss 89, which projects from one side of the sprocket 81, the portion 89 forming a drum upon which the cable 88 can be wound or unwound to move the gauge or weight 87 up and down in the operating box L. The gauge 87 is formed with a suitable pointer 90, which when in line with the marks or gauge lines 91 on the inner wall of the box L, designate or indicate the exact position of the locking bar 10, thus illustrating at a glance to the jailer operating the hand mechanism, the position of the gang-bar 10, cams 11 and the relative position of the unlocking bars 6, which is a very important feature in the successful operation of this invention. The gauge 87 performs the same functions as the indicator 40, illustrated in Figure 3, it being evident that the construction illustrated in Figures 13 and 14 are more adaptable to smaller jails, where a less expensive construction is desired, but in which equally effective results are obtainable.

In accordance with the patent statutes I have described the principles of operation of my invention, together with the apparatus which I now consider to represent the best embodiment thereof, but I desire to have it understood that the construction shown is only illustrative and that the invention can be carried out by other means and applied to uses other than those above set forth, within the scope of the following claims:

1. The combination in a door lock actuating device, of slideable doors, latch lugs on said doors, a locking bar for engaging said lugs to lock said door, a horizontal slideable cam for operating said locking bar into locking or unlocking position, fluid pressure devices connected in series to said slideable cam for operating said cam longitudinally and a master valve for controlling the operation of said fluid pressure devices to cause them to operate said horizontally slideable cam.

2. In combination with a series of slideable

doors, independent locking means for each of said doors, a movable member for simultaneously operating said locking means, a plurality of cylinders connected to said movable member at intervals throughout the length thereof, a source of fluid pressure and means for connecting said source of fluid pressure to said cylinders to operate the same.

3. The combination with a series of slideable doors, independent locking mechanism for each of said doors, operating means engaging said locking mechanisms to cause said locking mechanisms of said doors to be operated simultaneously, said operating means comprising a gang-bar having a series of cams fixed thereon for each of said door locking mechanisms and a fluid pressure device for operating said lock operating means to move said gang-bar longitudinally to operate the locking mechanisms of each of said doors simultaneously for the purposes specified.

4. The combination with a series of slideable doors, independent locking mechanisms for each of said doors, a longitudinally slideable gang-bar having means for connecting with and operating said door locking mechanisms, a fluid pressure device for operating said gang-bar to cause said door locking mechanisms to be operated simultaneously to lock or unlock said doors and enclosed indicating means adapted to indicate the position and operation of said gang-bar and door locking mechanisms.

5. A locking device for slideable doors, said device including horizontally slideable cam members having a series of cam faces formed thereon, a gang-bar connecting said cam members, a vertically slideable locking bar, latch lugs fixed to said doors having notches which are adapted to be engaged by said locking bar when the same is in locking position, a vertically movable yoke adapted to ride on said cam member and to be reciprocated vertically by the cam faces of said cam member, means connecting said yoke with said locking bar and fluid power means for reciprocating said gang-bar horizontally to operate said locking bar.

6. A locking device for a series of slideable doors, said device including a vertically slideable locking bar, notched latch lugs secured to each door adapted to be engaged by said locking bar, key operated locking means for engaging one of said latch lugs, a vertically movable yoke connected to said locking bar, a gang-bar having a series of cam faces for operating said yoke to hold said locking bar in locked open and dead-locked positions, the cam faces intermediate the locked open and dead-locking cam faces holding said yoke and locking bar free to be moved vertically by said key locking mechanism to unlock any of said doors in

- dividually and fluid power means for operating said gang-bar to set any of said cam faces into engagement with said yoke for operating said locking bar.
5. A locking device for a series of slideable doors, said device including a horizontally movable controlling bar, fluid pressure cylinders for operating said controlling bar, a source of fluid pressure means connecting 65 said cylinders with said source of fluid pressure, a master valve interposed between said cylinders and said source of fluid pressure, said master valve being adapted to direct said fluid pressure to either side of the 70 pistons of said cylinders to move the same simultaneously in the same longitudinal direction to operate said controlling bar in a similar direction, the means connecting said cylinders with said source of fluid pressure 75 being adapted to be filled with fluid at all times, an exhaust port connected with said master valve to allow the escapement of the surplus fluid in said connecting means when the pistons in said cylinders are operated, 80 20 sure being adapted to be filled with fluid at all times, an exhaust port connected with said master valve to allow the escapement of the surplus fluid in said connecting means when the pistons in said cylinders are operated by fluid pressure.
8. A locking device for a series of slideable doors, including slideable locking bars for each of said doors, a gang operating bar, cam faces on said gang-bar, means connecting said locking bars with the cam faces on said gang-bar, a fluid pressure device for operating said gang-bar, a controlling valve for directing fluid pressure to said fluid pressure operating device to cause said gang-bar to be reciprocated longitudinally by said fluid pressure device, key operated locking means for each of said doors and a ratchet locking means for each of said doors to hold 90 40 said doors against movement in an open direction when said ratchets are in operation, said cam faces on said controlling bar being adapted to operate said locking bars of said doors simultaneously when said controlling bar is operated by said fluid pressure device to dead-lock said locking bar against movement in one position, to release said locking bar so as to be operated by said key locking means in another position, to release said 95 50 ratchet locks simultaneously in a third position, fourth, to lock said locking bar against movement in open position, for the purposes specified.
9. A locking device for a series of slideable doors, including a slideable locking bar for each door, a gang controlling bar for oper- 100 ating said locking bar into four distinct positions, fluid pressure devices for operating said controlling bar, said fluid pressure devices being all connected in series to said 105 gang controlling bar and a master valve for connecting said fluid pressure devices with a source of fluid pressure so as to operate said fluid pressure devices to move said controlling bar into said four positions for the 110 purposes specified.
10. The combination with a circular prison, of a plurality of slideable doors, with independent locking bars, key operated locking means for each of said doors, ratchet locking means for each of said doors, a curved controlling bar having means for operating said locking bars, key operated locking means and said ratchet locking means simultaneously, fluid pressure devices 115 connected in series for operating said curved controlling bar, a master valve for controlling said fluid pressure devices and indicating means to indicate the position of said curved controlling bar for the purposes 120 specified.
11. In combination with a door having a latch lock, a vertically slideable latch-bar adapted to engage said latch-lock, a yoke secured to the upper end of said latch-bar having upper and lower cam engaging portions positioned in fixed relation to one another, a gang-bar slideable through said yoke and a cam plate secured to said gang-bar having off-set cam portions of a width equal to the distance between said cam engaging portions of said yoke and adapted to be engaged thereby for holding said latch-bar in dead locked or open position, and another portion of said cam plate of a width less than the distance between said cam engaging portions of said yoke adapted to be engaged thereby for permitting said latch-bar to be manually raised from said latch-lock at will.
12. A locking device for a series of slideable doors, including a slideable locking bar for each door, a longitudinally slideable gang controlling cam bar for operating said locking bars, pressure cylinders for operating said controlling bar, pipes connecting said cylinders in series with each other and a master valve connected with said connecting means adapted to direct and control pressure to cause the pressure cylinders to operate longitudinally said gang cam bar in either direction into various positions and said pipes connecting said cylinders acting as intake and exhaust pipes from said valve automatically to cause said cylinders to operate said controlling bar in either direction for the purposes specified.

JOHN ALLENSON.
